ART OF TREATING LEATHERBOARD

Herman W. Richter, Bridgewater, Mass., assignor
to George O. Jenkins Company, Bridgewater,
Mass., a corporation of Massachusetts

Application November 18, 1936, Serial No. 111,449

15 Claims. (Cl. 92—40)

This is a continuation in part of my copending application Serial No. 77,955, filed May 5, 1936.

This invention relates to the art of treating leatherboard, and has particular reference to methods for producing variegated cross-sectional color effects in a sheet of leatherboard.

Leatherboard, which is often termed "heeling board" because of its wide use in the shoe industry, is a material made from a furnish composed principally of leather scrap or waste by board making processes. These processes involve disintegration in a beating engine and subsequent formation into sheets or slabs on a wet machine. The product usually contains various amounts of other ingredients such as paper. In this specification the term "leatherboard" will be used to denote such a product without regard to the proportions of constituents.

Leatherboard, as made prior to Patent No. 1,975,556 issued to me on October 2, 1934, was invariably of a rather dark, unattractive hue, due undoubtedly to the presence of iron-tannate inks produced in the board during its fabrication. In the aforesaid patent I disclose a method for eradicating the iron-tannate inks or "saddening material" and liberating the natural color of the leather fibre by subjecting leatherboard to the action of certain bleaching agents. The customary way of carrying out the process on a commercial scale is to dip the leatherboard, after it has been deprived of its excess moisture, in a dilute aqueous solution of the bleaching agent.

The sheet of leatherboard is left in the bleaching solution until the desired result is produced. If a uniform light color throughout the board is desired, the sheet of leatherboard is kept in the solution until penetration is complete. By arresting the action of the chemical before complete penetration takes place, it is possible to produce a sheet of leatherboard whose outer cross-sectional zones are considerably lighter than its central zone or core, so that a single thickness of leatherboard appears as if it were made by uniting a thin sheet of light colored leather or leatherboard to each side of a thin sheet of darker colored leather or untreated leatherboard. The relative thicknesses of the light and dark zones can be controlled within certain limits. Heel lifts may be dinked out of this material and built up into heels. After the heel is treated with the usual stains and dressings employed in heel finishings, its circumferential surface presents an attractive variegated appearance in sharp contrast to the heels of the prior art which were built up from ordinary leatherboard. Furthermore, the heel appears on a casual inspection to have been made of alternate layers of light and dark colored lifts, whereas as a matter of fact, all the layers were dinked

out of the same or similarly treated material. This procedure, therefore, results in considerable economy in labor and material, as it is not necessary to prepare more than one kind of material or to sort the lifts during the heel building operation.

Substantially the same variegated effects in heels can be produced by chemically treating the leatherboard so that one or more desired cross-sectional zones thereof are darkened in shade in respect to other cross-sectional zones thereof instead of being rendered lighter in color.

I have discovered that one or more chemicals for producing either a darker or a different colored shade can be applied to selected layers of the leatherboard as they are being built up on the wet machine. This renders it possible to produce directly on the wet machine a leatherboard product which has one or more darkened or colored and one or more bleached or normal colored cross-sectional zones. As one example of a possible product made on a wet machine by said method may be mentioned a board having a darkened or colored central core and unchanged outer cross-sectional zones. The chemicals for coloring or bleaching the selected layers of board may be applied by spraying, by a transfer roll or by any other suitable means so that they may be applied intermittently. Since spraying is my preferred embodiment I shall refer to it in the specification more particularly than to other methods but my invention is not limited to spraying.

The intermittent treatment of the board as it is being built up on the wet machine is not necessarily limited to the application of chemicals adapted to darken or color one or more cross-sectional zones of the board. Bleaching agents may be applied in the same way. It is therefore possible to produce directly on the wet machine a slab of leatherboard which has one or more bleached cross-sectional zones. As one example of a product made on a wet machine in the foregoing manner may be mentioned a leatherboard product having a bleached central core and unchanged outer cross-sectional zones.

By combining the two chemical treatments it is possible to build up directly on the wet machine a leatherboard product having certain bleached cross-sectional zones and certain other darkened or colored cross-sectional zones. Likewise, it is possible to produce other variegated effects such as combinations of bleached, unbleached, colored and darkened zones.

The application of the bleaching, coloring and/or darkening chemical to the board as it is being built up on the wet machine renders it possible to produce boards of variegated cross-section having thicknesses greater than previously considered practical without the use of adhesives or other securing means. The use of

such boards in the manufacture of shoe heels results in considerable economy as obviously less lifts are necessary to build a heel of a given height.

5 One object of this invention is to produce directly on the wet machine a leatherboard product having one or more darkened or colored cross-sectional zones, the rest of the board being either bleached or the natural color of leatherboard.

10 Another object is to produce an integral built up slab or sheet of leatherboard of variegated cross-sectional hues or colors and having a thickness greater than previously considered practical 15 without the use of adhesives or other securing means.

Another object is to produce the product of the foregoing objects without the use of expensive materials or chemicals or complicated apparatus 20 and without injuriously affecting the leather fibre.

Still another object is to provide a relatively simple method and procedure for carrying out each of the foregoing objects.

25 In one of its aspects, the method of the invention consists in intermittently spraying leatherboard as it is being built up on the wet machine with a chemical or chemicals capable of reacting with a material normally present in the 30 board to produce a darker shade or a different color than the usual color of the board. In this aspect, the invention depends in part upon the fact that leather-containing materials normally contain various organic compounds such as tannins, proteins, glucose, etc. capable of reacting with a wide range of chemicals to produce shades or hues different from the usual color of leatherboard. Leatherboard also appears to contain sulphur in sufficient concentration to produce a 40 dark coloration with various chemicals. Leatherboard made in whole or in part from chrome-tanned leather scrap as distinguished from vegetable tanned leather scrap contains chromium oxide as well as various other chemicals so that 45 additional chemicals may be used for spraying such leatherboard to produce colors therein different from the normal color imparted by such leatherboard stock.

In another of its aspects, the method of the 50 invention consists in intermittently spraying leatherboard as it is being built up on the wet machine with two or more chemicals which are capable of reacting within the material to produce deeper shades or different colors than the 55 usual color of leatherboard. In this aspect, the invention depends in part upon the fact that various chemicals may be introduced into leatherboard some time during its fabrication or subsequently thereto which are capable of reacting 60 with a wide range of chemicals to produce deeper shades or different colors than the usual color of leatherboard.

In another of its aspects, the method of the 65 invention consists in intermittently spraying leatherboard as it is being built up on the wet machine with two or more chemicals which are capable of reacting within the material to produce lighter shades or hues than the usual color of leatherboard.

70 In another aspect, the method of the invention consists in intermittently spraying or otherwise intermittently treating the leatherboard as it is being built up on the wet machine with either one or a plurality of chemicals to ultimately 75 produce a different color or colors in the cross-

sectional zone or zones which are sprayed from the normal leatherboard color in the untreated cross-sectional zone or zones.

In another aspect, the method of the invention consists in selectively spraying different cross-sectional zones with different chemicals as the leatherboard is being built up on the wet machine to thereby produce different color effects in different cross-sectional zones.

Referring now briefly to the drawings,

Fig. 1 is a view in perspective of a sheet of board treated so that one outer cross-sectional zone is darker or of a different color than the rest of the material;

Fig. 2 is a perspective view of a heel lift dinked out of the material of Fig. 1;

Fig. 3 is a view in perspective of a sheet of board treated so that both outer cross-sectional zones are darker or of different color than the central zone;

Fig. 4 is a perspective view of a heel lift dinked out of the material of Fig. 3;

Fig. 5 is a perspective view of a heel lift made from a sheet of leatherboard which has been processed so that its central zone is darker or of a different color than the rest of the material;

Fig. 6 is a perspective view of a sheet or slab of leatherboard of greater thickness than those in the preceding figures and having a plurality of alternating dark colored and lighter colored zones;

Fig. 7 is an elevation of a heel which may have been built up of the heel lifts of Figs. 2, 4 or 5 or from heel lifts dinked out of the board shown in Fig. 6;

Fig. 8 is a side elevation of what I shall refer to as the wet machine with parts broken away and shown in section; and

Fig. 9 is an enlarged plan view of the suction box looking in the direction of the arrows 9-9 in Fig. 8.

The leatherboard stock is made in the usual manner in the beater (not shown) and is thence conducted to a storage tank or chest (not shown) from whence it is conducted to the vat 10 in which the cylinder mold 11 is rotatably mounted. The "wet machine" as referred to in this specification and the claims comprises the cylinder mold 11, the endless felt belt 12, the various carrier rolls 13, the couch roll 14, the bottom press 5 roll 15 and the top press roll 16.

In normal operation the cylinder mold is rotated in the direction of the arrow and continuously picks up a thin web of leatherboard stock on its outer surface, and this web is continuously transferred to the surface of the moving felt belt and carried by it between the top and bottom press rolls 15 and 16, where water is squeezed from the web and deposited in the trough 17. At this stage the top press roll 16 continuously picks up the thin web of leatherboard from the felt until the leatherboard stock wound upon said roll has been built up to the required thickness, when the cylindrical sheet of leatherboard retained on the roll is cut longitudinally to form a rectangular sheet which is deposited upon the table 18 and then conveyed to the dryer. The top press roll then again picks up another leatherboard web from the felt to thus build up the next leatherboard sheet.

In accordance with one embodiment of my invention, I provide one or more sprays 19 or 20 which are adapted to spray one or more chemicals upon certain selected layers of leatherboard as they are being built up on the wet machine to 7

thus provide cross-sectional zones of contrasting color in each completed sheet of leatherboard.

The spray or sprays may be located as at 19 or as at 20, or in any other convenient place so that each may be operated to spray a given length of the leatherboard web after it leaves the level of the leatherboard stock in the vat 10.

If the sprays are located between the vat and the press rolls 15 and 16, I prefer to use a suction box 21 to remove some of the water from the leatherboard web before it is sprayed with the chemical. The use of a suction box accomplishes at least two functions; it reduces the loss of the chemical or chemicals subsequently sprayed upon the leatherboard, and it also avoids crushing of the leatherboard when the liquids are squeezed out between the top and bottom press rolls. If a suction box is not used and the sprays are located at 19, and if the chemicals added to the leatherboard web by the sprays increase the liquid content thereof too much, this greater quantity of liquid when squeezed out between top and bottom rolls will disrupt or crush the structure of the leatherboard. When the sprays are located at 20 the use of a suction box may be unnecessary, since in such arrangement most of the liquid is removed by the top and bottom rolls before the sprayed chemical reaches the leatherboard.

I have found that by using about five and one-half inches of vacuum on the suction box water is sucked from the thin leatherboard web through the holes 22 in the top of the suction box, thus transforming the glistening leatherboard web to a dull web which is then in satisfactory condition for the subsequent spraying operation.

To produce some variegated cross-sectional effects the spray of one chemical is turned on while colored thicknesses of the board are being built up and shut off as normal colored layers are being built up. If the spray is shut off as the central zone or core of the board is being built up, the product has a normal colored central zone and outer zones of the color imparted by the chemical which is being sprayed. (See Fig. 3.) The opposite result (see Fig. 5) can be produced by shutting the spray off as the outer layers or thicknesses are being fabricated and turning it on as the central zone is being built up. I may produce a board having as many alternate layers of various colors as may be desired. It should be noted at this point that generally speaking a greater concentration of chemical is necessary when the chemical is applied as a spray on the wet machine than when the fabricated board is immersed in the chemical solution or sprayed therewith. The reason is that the board as it is being built up on the machine contains a substantial amount of water which serves to dilute the chemical.

Instead of spraying the material as it is being built up on the wet machine with a chemical to color certain of its zones, I may spray the material intermittently with a bleaching agent to produce a variegated color effect. Thus the spray is turned on while desired light colored thicknesses of board are being built up and shut off as layers of ordinary leatherboard are being built up. If the spray is shut off as the central zone or core of the board is being built up, the product is similar to that produced by immersing the fabricated board in a bleaching solution for an insufficient time to secure complete penetration, i. e., the board will have a dark or dull central zone and lighter outer zones. The opposite re-

sult can be produced by shutting the spray off only as the outer layers are being fabricated. I may produce a board having as many alternate layers of bleached and unbleached board as may be desired.

Additional pleasing variegated effects can be produced by spraying certain layers of the board as it is being built up on the wet machine with bleaching agents and certain other layers with one or more chemicals tending to either color or darken the layers. If desired certain of the layers may be left untreated so that the finished board has zones of several different shades. Likewise greater intensities of bleaching, coloring or darkening effects can be produced in a single cross-section of board by spraying the different layers with different concentrations of chemicals or bleaching agents.

In Fig. 6 is illustrated a slab of leatherboard which was built up on the wet machine with a plurality of alternating darker and lighter cross-sectional zones. The lighter zones may be produced by the use of bleaching agents, in which case the zones which appear dark may be treated with a darkening chemical, a coloring chemical, or left untreated. A variation consists in leaving untreated the zones which are to appear light and in treating the other zones with a darkening or coloring chemical. The slab shown in Fig. 6 is as thick as several conventional lifts so that its employment in the building of heels results in considerable economy.

To produce a bleached cross-sectional zone the spray is supplied with a solution of any bleaching agent for leatherboard such as those disclosed in my Patent No. 1,975,556.

To produce a darkened or colored cross-sectional zone the spray may be supplied with any one or more of a large group of chemicals. For example, aniline dyes, such as "Azo Yellow," "Acid Orange," "Nigrosine" (black) "Chrysoidine" (brown) may be used or emulsified pigment suspensions may be used.

Also solutions of chemicals which react with normal constituents of the leatherboard stock may be used, such as ferric chloride, ferric sulphate, lead acetate, sodium iodate, potassium permanganate, potassium bichromate, or ammoniacal solutions of silver nitrate. In the use of a solution of ferric chloride, for example, the iron in the solution reacts with the tannic acid in the leatherboard to produce the very dark color of a concentrated iron tannate ink. In the use of lead acetate this chemical apparently reacts with sulphur which is normally present in the leatherboard to produce dark colored lead sulphide.

Also a dischargeable dye, such as "Acid Orange" may be incorporated in the leatherboard stock in the beater and the web may be sprayed with a chemical known in the trade as a "discharge", for example, sodium hydrosulphite or stannous chloride, to thus localize the dye in certain localities of the leatherboard.

Also two or more chemicals which are adapted to react in the leatherboard to form colored compounds therein may be used. One of the chemicals may be introduced into the leatherboard stock in the beater and another sprayed on a selected cross-sectional zone or zones on the wet machine, thus causing the reaction to take place only in the zones sprayed. Or the reacting chemicals may both be sprayed upon a selected cross-sectional zone or zones on the wet machine, thus coloring only that zone. Or one of the chemicals

may be sprayed on a selected cross-sectional zone on the wet machine and another reacting chemical applied to the board by dipping after the board has been dried, thus coloring only that zone

5 or zones which have been previously sprayed on the wet machine. For example the use first of barium chloride and then of potassium chromate will cause the formation of the yellow barium chromate pigment.

10 Although in the foregoing specification I have described the use of sprays for applying the chemicals to the desired length of leatherboard web, it will be apparent to those skilled in this art that the chemicals may be applied in other

15 art that the chemicals for changing the normal color of the leatherboard stock may be applied to any given length of the web on the wet machine by the use of various other means. For example, similarly located transfer rolls may be used in-

20 instead of sprays. Thus a felt covered transfer roll treated with the chemical may be rotated in contact with one surface of the web to thereby transfer the chemical to the web, and said roll may be mounted for movement out of contact with the web when untreated lengths thereof are being

28 built up.
Another method of applying chemical to a given length of web is to treat a given length of the felt belt 12 therewith prior to the point where it picks up the leatherboard web from the cylin-
29

30 der mold 11, the chemical being transferred from belt to web. The chemical may be applied to a given length of belt by the use of a spray, transfer roll, passing the belt directly through a tank containing the chemical, or in any other suitable

35 manner. In the use of this method it is advisable to thoroughly wash retained chemical from the belt before it contacts portions of the web which are to be left untreated, for otherwise chemical retained in the belt may discolor such portions of

40 the web. This washing may be accomplished by the use of conventional showers and whippers (not shown) located between the bottom press roll 15 and the point where the chemical is applied to the belt.

45 Wherever in this specification or in the appended claims, I refer to a color or colors differing from the normal color of the leatherboard or from the color imparted by leatherboard stock I intend to include any darker or lighter hue of the

50 color imparted by the leatherboard stock as well as bleached leatherboard and white or black. Thus a color differing from the color imparted by the leatherboard stock may be produced by the use on the wet machine of bleaches, dyes or any

55 of the other chemicals or combinations of chemicals disclosed in this specification to produce a white, black, bleached, or colored or shaded zone or zones in leatherboard of a color or colors, shade or shades, hue or hues differing from the color or

60 colors, shade or shades, hue or hues which each of said zones would have if they had not thus been treated on the wet machine.

It is understood that the foregoing disclosure is illustrative of my invention and that many chemicals other than those disclosed may be used to impart color differing from the normal color of the leatherboard without departing from the scope of the claims. It is also to be understood that my invention is not dependent upon any explanations or theories which I have set forth as descriptive of the actions involved, nor dependent upon the soundness or accuracy of any theoretical statements so advanced.

I claim:

75 1. The method of making sheet leatherboard

having a varicolored cross section and useful in the manufacture of heel lifts, which comprises; forming a web from a furnish of fibrous material on a wet machine, advancing said web and intermittently spraying the web as it is being built up on a roll of the wet machine with a substance which changes the color of the web, and thereby forming a definite color stripe on the edge face of the sheet accumulating on the roll.

2. The method of making sheet leatherboard having a varicolored cross section and useful in the manufacture of heel lifts, which comprises; forming a web from a furnish of fibrous material on a wet machine, advancing said web and intermittently treating the web as it is being built up on a roll of the wet machine with a substance which changes the color of the web, and thereby forming a definite color stripe on the edge face of the sheet accumulating on the roll.

3. The method of making sheet leatherboard 21 having an edge face exhibiting stripes of color substantially parallel to its flat faces and useful in the manufacture of heel lifts, which comprises; forming a web of fibrous material on a wet machine, advancing said web to be wound on a roll 22 of the wet machine and treating spaced longitudinal portions of the running web throughout the width thereof with a substance which changes the color thereof in contrast to that of the untreated intervening portions, the length of each of said 30 treated portions being such as to provide a definite color stripe on the edge face of the sheet accumulating on the roll.

4. The method of making sheet leatherboard having an edge face exhibiting stripes of color substantially parallel to its flat faces and useful in the manufacture of heel lifts, which comprises; forming a web of fibrous material on a wet machine, advancing said web to be wound on a roll of the wet machine and spraying spaced longitudinal portions of the running web throughout the width thereof with a substance which changes the color thereof in contrast to that of the unsprayed intervening portions, the length of each of said sprayed portions being such as to provide a definite color stripe on the edge face of the sheet accumulating on the roll. 31 41

5. The method of making sheet leatherboard having a varicolored cross section and having at least one cross-sectional zone of a color different from the color imparted by the leatherboard stock, which method comprises; forming a web from a furnish of leatherboard stock on a wet machine, winding the web upon a roll of the wet machine to build up a sheet of the desired thickness, and selectively treating the portion of the web which is to form said different colored cross-sectional zone, while said portion of the web is on the wet machine, with a substance which imparts to said portion of the web a color different from the color imparted by the leatherboard stock. 50 55 60

6. The method of making sheet leatherboard having a varicolored cross section and having at least one cross-sectional zone of a color different from the color imparted by the leatherboard stock, which method comprises; forming a web from a furnish of leatherboard stock on a wet machine, winding the web upon a roll of the wet machine to build up a sheet of the desired thickness, and selectively spraying the portion of the web which is to form said different colored cross-sectional zone, while said portion of the web is on the wet machine, with a substance which imparts to said portion of the web a color differ- 65 70

ent from the color imparted by the leatherboard stock.

7. The method of making sheet leatherboard having a varicolored cross section and having at least one bleached cross-sectional zone, which method comprises; forming a web from a furnish of leatherboard stock on a wet machine, winding the web upon a roll of the wet machine to build up a sheet of the desired thickness, and selectively treating the portion of the web which is to form said bleached cross-sectional zone, while said portion of the web is on the wet machine, with a bleaching agent which bleaches said portion of the web.

8. The method of making sheet leatherboard having a varicolored cross section and having its outer cross-sectional zones of a color imparted by the leatherboard stock and a central cross-sectional zone of different color, which method comprises; forming a web from a furnish of leatherboard stock on a wet machine, winding the web upon a roll of the wet machine to build up a sheet of the desired thickness, and selectively treating the portion of the web which is to form said central cross-sectional zone, while said portion of the web is on the wet machine, with a substance which imparts to said portion of the web a color different from the color imparted by the leatherboard stock.

9. The method of making sheet leatherboard having a varicolored cross section and having its outer cross-sectional zones of a color imparted by the leatherboard stock and a central cross-sectional zone of different color, which method comprises; forming a web from a furnish of leatherboard stock on a wet machine, winding the web upon a roll of the wet machine to build up a sheet of the desired thickness, and selectively spraying the portion of the web which is to form said central cross-sectional zone, while said portion of the web is on the wet machine, with a substance which imparts to said portion of the web a color different from the color imparted by the leatherboard stock.

10. The method of making sheet leatherboard having a varicolored cross section and having its outer cross-sectional zones of a color imparted by the leatherboard stock and a bleached central cross-sectional zone, which method comprises; forming a web from a furnish of leatherboard stock on a wet machine, winding the web upon a roll of the wet machine to build up a sheet of the desired thickness, and selectively treating the portion of the web which is to form said central cross-sectional zone, while said portion of the web is on the wet machine, with a bleaching agent which bleaches said portion of the web.

11. The method of making sheet leatherboard having a varicolored cross section and having a central cross-sectional zone of a color imparted by the leatherboard stock and outer cross-sectional zones of a different color, which method comprises; forming a web from a furnish of leatherboard stock on a wet machine, winding the web upon a roll of the wet machine to build up a sheet of the desired thickness, and selectively treating the portions of the web which are to form said outer cross-sectional zones, while said portions of the web are on the wet machine, with a substance which imparts to said portions of the web a color different from the color imparted by the leatherboard stock.

12. The method of making sheet leatherboard

having a varicolored cross section and having a central cross-sectional zone of a color imparted by the leatherboard stock and outer cross-sectional zones of a different color, which method comprises; forming a web from a furnish of leatherboard stock on a wet machine, winding the web upon a roll of the wet machine to build up a sheet of the desired thickness, and selectively spraying the portions of the web which are to form said outer cross-sectional zones, while said portions of the web are on the wet machine, with a substance which imparts to said portions of the web a color different from the color imparted by the leatherboard stock.

13. The method of making sheet leatherboard having a varicolored cross section and having a central cross-sectional zone of a color imparted by the leatherboard stock and bleached outer cross-sectional zones, which method comprises; forming a web of leatherboard stock on a wet machine, winding the web upon a roll of the wet machine to build up a sheet of the desired thickness, and selectively treating the portions of the web which are to form said bleached outer cross-sectional zones, while said portions of the web are on the wet machine, with a bleaching agent which bleaches said portions of the web.

14. The method of making sheet leatherboard having a varicolored cross section and having at least two cross-sectional zones of colors differing from each other and from the color imparted by the leatherboard stock, which method comprises; forming a web from a furnish of leatherboard stock on a wet machine, winding the web upon a roll of the wet machine to build up a sheet of the desired thickness, selectively treating the portion of the web which is to form one of said different colored cross-sectional zones, while said portion of the web is on the wet machine, with a substance which imparts to said portion of the web a color different from the color imparted by the leatherboard stock, and subsequently selectively treating the portion of the web which is to form another of said different colored cross-sectional zones, while said latter portion of the web is on the wet machine, with a substance which imparts to said portion of the web a color different from the color imparted to the aforesaid portion of the web and different from the color imparted by the leatherboard stock.

15. The method of making sheet leatherboard having a varicolored cross section and having at least two cross-sectional zones of colors differing from each other and from the color imparted by the leatherboard stock, which method comprises; forming a web from a furnish of leatherboard stock on a wet machine, winding the web upon a roll of the wet machine to build up a sheet of the desired thickness, selectively spraying the portion of the web which is to form one of said different colored cross-sectional zones, while said portion of the web is on the wet machine, with a substance which imparts to said portion of the web a color different from the color imparted by the leatherboard stock, and subsequently selectively spraying the portion of the web which is to form another of said different colored cross-sectional zones, while said latter portion of the web is on the wet machine, with a substance which imparts to said portion of the web a color different from the color imparted to the aforesaid portion of the web and different from the color imparted by the leatherboard stock.

HERMAN W. RICHTER.
